UNITED STATES PATENT OFFICE

164,355

HOLDER DEVICE FOR A HANDBAG OR SIMILAR ARTICLE

Edward M. Davis, Brooklyn, N. Y.

Application April 6, 1950, Serial No. 9,005

Term of patent 14 years

(Cl. D87—2)

To all whom it may concern:

Be it known that I, Edward M. Davis, a citizen of the United States and a resident of Brooklyn, county of Kings, State of New York, have invented a new, original, and ornamental Design for a Holder Device for a Handbag or Similar Article, of which the following is a specification, reference being had to the accompanying drawings, forming part hereof and in which:

Fig. 1 is a side elevational view of a holder device for a handbag or similar article embodying my new design with the suspension arm in up-raised position.

Fig. 2 is a similar view to Fig. 1 but with the suspension arm in a lowered position.

Fig. 3 is a rear elevation of the device as shown in Fig. 2, and

Fig. 4 is a top plan view thereof as shown in Fig. 2.

The dominant feature of my design resides in the particular grooved post member near one end of the rectangular plate member, said post

being provided with a vertically swinging suspension arm, all as shown.

I claim:

The ornamental design for a holder device for a handbag or similar article, substantially as shown and described.

EDWARD M. DAVIS.
